Augustus C. Mueller, of St. Louis, Mo.

ass. to

Heller and Leibrock, of Mascoutah, Illinois.

Letter Patent No. 2191, Dated Oct. 10, 1865.

Design for a Trade Mark.

The schedule referred to in these Letter Patent and making part of the same.

shall whom it may concern:

Be it known that I, Augustus C. Mueller, of the City and County of St. Louis, and State of Missouri, have invented a design for a new Trade Mark, it being a "Brand for Grain Barrels," and I do hereby declare that the following is a full, clear and exact description thereof, reference being had to the accompanying drawings, forming a part of this specification.

The accompanying drawings fully describe the nature of this invention. The words "Old Mascoutah St. Co." are painted in large capital letters around a circle described from the center of the barrel head, said circle being drawn about two and one half inches, more or less, from the chime of the barrel. In the upper portion of the circular area which is enclosed by the above described circle are the figures "196," at either end of which figure is a small ornamental scroll. Immediately below the figures "196" are three stars arranged across the head, and below these again is another ornamental scroll. Beneath the last named scroll the names Leibrock and Heller are painted in capital letters one inch long, more or less. The names Leibrock and Heller are arranged in a curved line across the barrel head, and below them are the letters "Ilo," in capitals, on either end of which is another scroll.
